ELECTRICAL CONDUCTOR SPLICING SLEEVE

Maurus C. Logan, Elizabeth, N. J., assignor to The Thomas & Betts Co., Elizabeth, N. J., a corporation of New Jersey

Application October 24, 1955, Serial No. 38,535

Term of patent 14 years

(Cl. D26—1)

Fig. 1.

Fig. 2.

Fig. 3.

Fig. 4.

Fig. 5.

Fig. 1 is a top plan view of an electrical conductor splicing sleeve, showing my new design;

Fig. 2 is a similar view showing the electrical conductor splicing sleeve in a position having a ninety degree angular relation to the position thereof shown in Fig. 1;

Fig. 3 is an end view thereof;

Fig. 4 is a longitudinal sectional view taken on the line 4—4 of Fig. 1, showing the inner metal sleeve in elevation; and

Fig. 5 is a longitudinal sectional view taken on the line 5—5 of Fig. 2.

A portion of the drawing figures is diagonally lined to indicate transparency.

I claim:

The ornamental design for an electrical conductor splicing sleeve, as shown and described.
